[57] CLAIM

The ornamental design for a bottle holder for vehicles, as shown and described.

DESCRIPTION

FIG. 1 is a top, front, and right side perspective view of a bottle holder for vehicles showing my new design; FIG. 2 is another top, front, and right side perspective view thereof with the bottle holder in a folded condition;

FIG. 3 is a top plan view thereof;

FIG. 4 is a bottom plan view thereof;

FIG. 5 is a front elevational view thereof;

FIG. 6 is a rear elevational view thereof; and

FIG. 7 is a right side elevational view thereof, the side opposite being similar thereto.

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 279,836
